UNITED STATES PATENT OFFICE

149,958

DESIGN FOR A FORK OR OTHER ARTICLE OF FLATWARE

Isadore Albert Lipman, Meriden, Conn., assignor to The Ellmore Silver Company, Inc., Meriden,
Conn., a corporation of Connecticut

Application March 24, 1947, Serial No. 137,825

Term of patent 14 years

(Cl. D54—12)

To all whom it may concern:

Be it known that I, Isadore A. Lipman, a citizen of the United States, residing in the city of Meriden, county of New Haven, and State of Connecticut, have invented a new, original, and ornamental Design for a Fork or Other Article of Flatware, of which the following is a specification, reference being had to the accompanying drawing, forming part thereof, and in which:

The essential features of my design reside in the parts shown in full lines.

I claim:

The ornamental design for a fork or other article of flatware, substantially as shown and described.

ISADORE ALBERT LIPMAN.
